CLAIM

The ornamental design for a straw cover, as shown and described.

DESCRIPTION

FIG. 1 is a front, right, and top perspective view of a straw cover, showing my new design;

FIG. 2 is a rear, left, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an alternative perspective view of the straw cover when in use.

The broken lines shown in the drawings depict portions of the straw cover that forms no part of the claimed design.
